UNITED STATES PATENT OFFICE.

GEORGE V. AHARA, OF TORONTO, ONTARIO, CANADA, ASSIGNOR TO FAIRBANKS,
MORSE & COMPANY, OF CHICAGO, ILLINOIS, A CORPORATION OF ILLINOIS.

IGNITION APPARATUS FOR INTERNAL-COMBUSTION ENGINES.

1,104,860.

Specification of Letters Patent. Patented July 28, 1914.

Application filed June 5, 1913. Serial No. 771,815.

To all whom it may concern:

Be it known that I, GEORGE V. AHARA, a citizen of the United States of America, and resident of the city of Toronto, county of York, Province of Ontario, in the Dominion of Canada, have invented a certain new and useful Improvement in Ignition Apparatus for Internal-Combustion Engines, of which the following is a specification.

10 The invention consists in the novel construction and arrangement of parts, whereby the magneto is operated from the fuel pump operating mechanism and said mechanism is so arranged that the spark may be advanced or retarded in relation to the movement of the crank shaft.

The objects of the invention are, to simplify the means for operating the magneto in a jump spark ignition apparatus as used 20 on commercial types of stationary internal combustion engines, utilizing part of the ordinary mechanism to operate the magneto.

A further object is to provide a simple 25 and easily operated means for advancing or retarding the spark.

In the drawings, Figure 1 is a perspective view of the improved device shown assembled and as placed upon an engine. Fig. 2 30 is an enlarged vertical longitudinal sectional view of part of the main operating rod showing the means for advancing or retarding the spark. Fig. 3 is an enlarged perspective view of the rocker arm for operating the magneto.

Like numerals of reference indicate corresponding parts in each figure.

Referring to the drawings 1 is a bracket which is especially designed to be screwed 40 to the side face of the engine cylinder and the said bracket is formed with an upwardly projecting portion having a horizontal shelf 2 extending outwardly therefrom which is adapted to support the magneto 3. The bracket 1 is also formed with 45 a forwardly projecting portion 4 extending from the lower side thereof, said forwardly projecting portion having a downwardly extending lug portion 5 in which is secured a 50 pivot pin 6.

7 is a rocker arm having a hollow cylindrical bearing portion 8 at the lower end journaled upon the pin 6. The arm extends angularly upwardly and forwardly from the journal portion 8 and terminates in a vertical portion 9 at the outer end. The rocker arm 7 is formed substantially U-shape in cross section the hollow side being turned toward the bracket 1.

10 is a longitudinal slot formed in the 60 front side of the upper portion 9 of the arm 7.

11 is a handle rigidly secured in the upper end of the arm 7 and extending horizontally outward therefrom.

12 is a lug projecting laterally from one side of the upright portion 9 of the arm 7 having a pin hole 13 therein.

14 are a pair of lugs formed integral with the lower journal portion 8 of the arm 7 70 and extending laterally therefrom in approximately right angular relation to the said arm.

15 is the engine cam shaft which is suitably supported in its bearing in the engine 75 frame and suitably operated.

16 is a pin rigidly secured in and extending laterally from the cam 17 secured on the end of the cam shaft 15, said pin bearing arranged off center from the cam shaft and 80 adapted to rotate around the center thereof.

18 is a rod having a journal bearing 19 secured on one end thereof and encircling the pin 16 and rotatably held thereon.

20 is a sleeve member adapted to slide on 85 the forward end of the rod 18 and having the forward end 21 rotatably supported on the pin 22 secured in the hole 13 in the lug 12 of the rocker arm.

23 is a nut secured on the outer end of the 90 pin 22 holding the sleeve 20 in place.

24 is a longitudinal rectangular shaped recess formed in the under side of the outer end portion of the sleeve 20 and communicating with the end of the cylindrical bore 95 25 of the sleeve 18. The top of the recess is covered in by an arched hood 26 forming part with the sleeve.

27 is a pin journaled in the sides of the end portion 21 of the sleeve member 20 and 100

extending across the recess 24 and having secured thereto within the slot the eccentric cam member 28, said pin also having a suitable handle or finger grip 29 at the outer 5 end. The cam 28 is formed of a disk of metal secured eccentrically upon the pin 27 and a portion 30 at one side thereof is flattened to abut the terminal end of the rod 18. The cam 28 thus forms a means for adjusting the distance between the centers of the pin 16 and the pin 22 as on the turning of the eccentric so that the narrow sides engage the end of the rod, the pin at the outer end will be moved closer to the end of the 15 rod and consequently closer to the operating pin 16.

31 is a collar encircling the rod 18 intermediate of its length and secured thereto.

32 is a spiral spring secured at one end to 20 the collar 31 and at the other end to the sleeve 20. The spring 32 normally holds the eccentric 28 in contact with the end of the rod 18 but allows the sleeve to be drawn forwardly without interfering with the action of the rod when it is desired to operate the rocker arm by means of the handle 11.

33 is the fuel pump rod pivotally secured to the lugs 14 and extending downward therefrom operating the fuel pump which is 30 of any ordinary construction and is not shown.

34 is a hardened steel block slidably arranged in the hollow end portion 9 of the rocker arm 7 and adjustably secured therein 35 by the bolts 35 extending through the slot 10 in said arm. The upper end of the block 34 is preferably beveled to one side.

36 is an arm secured to the magneto spindle and having an angularly set downwardly extending portion 37 formed with 40 its extremity beveled on both sides, the beveled end of the arm 37 being adapted to be engaged by the beveled block 34.

In the operation of this device, the rotation of the cam shaft 15 imparts a reciprocating motion to the rod 18 and such rod being pivotally connected to the rocker arm 7 swings the said rocker arm upon the pin 6, thereby reciprocating the pump rod and also 50 swinging the upper end of the arm forwardly to engage the magneto arm 36 and operate the armature. The block 34 is adjusted so that when the arm 7 moves to a point close to the limit of its forward stroke 55 the beveled end 37 of the arm 36 will slip over the point of the beveled block, the armature being returned to its normal position by the spring 38. As the arm 7 swings backwardly in its return movement the beveled end of the block 34 engages the opposite side of the beveled end 37 of the arm 36 60 operating the armature of the magneto in the opposite direction, the end of the arm 36

slipping over the point of the block 34 as the arm 7 reaches the limit of its return movement. The block 34 may be adjusted in the arm 7 to allow of the proper movement of the magneto arm.

In starting the engine it is desirable to retard the spark and the operation necessary 70 is very simple. The operator grasping the handle 11 swings the arm 7 forwardly drawing against the tension of the spring 32 and sliding the sleeve 20 on the rod 18. When the sleeve is thus moved forwardly the cam 28 is given a half turn so that the short side thereof is adjacent to the end of the rod and when the handle 11 is released the spring 75 draws the sleeve backwardly so that the end of the rod engages the short side of the said cam. The rod is thus shortened so that the forward operation of the rocker arm 7 will be somewhat retarded in relation to the movement of the cam shaft and consequently will be retarded in relation to the movement 85 of the engine piston causing the spark to occur at a later period. When the engine has fairly started the spark is advanced by swinging the rocker arm 7 forwardly and turning the eccentric cam 28 to bring the 90 long side into engagement with the rod 18 thus advancing the spark to the desired running position.

This construction of a sparking mechanism does not in any way interfere with the 95 hand operation of the fuel pump for priming purposes as the rocker arm 7 moves entirely independent of the movement of the rod 18 when operated through the handle 11.

Having thus described my invention what 100 I claim as new and desire to secure by Letters Patent is:

1. In an ignition apparatus for internal combustion engines, the combination with the magneto, of a rocker arm pivotally supported adjacent to the magneto and adapted to engage and operate it; a crank member suitably operated from the engine, a rod connected at one end to said crank member, a sleeve member slidably arranged on the free end of said rod and pivotally connected to said rocker arm; said sleeve member having a longitudinal slot therethrough, a cam arranged in said slot and rotatably supported in the sides of the sleeve and adapted to abut the end of said rod, and a spiral spring encircling said rod and secured at one end thereto and at the other end to said sleeve.

2. In an ignition apparatus for internal combustion engines, in combination, a 120 bracket adapted to be secured to the engine cylinder, a magneto rigidly supported on said bracket, an arm extending downwardly from the magneto armature, a rocker arm pivotally supported from the lower portion 125 of said bracket having an offset outer end

adapted to engage and operate said magneto arm, a crank member suitably operated from the engine, an adjustable rod connecting said crank and said rocker arm, and a pump rod connected to a lateral projecting lug on the lower end of said rocker arm. In witness whereof, I have hereunto sub-

scribed my name in the presence of two witnesses.

GEORGE V. AHARA.
